UNITED STATES PATENT OFFICE.

EMILE GÉRARD, OF LIMOGES, FRANCE, ASSIGNOR TO O. A. GAGER & CO.,
OF NEW YORK, N. Y.

DESIGN FOR A CUSPIDOR.

SPECIFICATION forming part of Design No. 21,324, dated February 2, 1892.

Application filed January 5, 1892. Serial No. 417,117. Term of patent 7 years.

To all whom it may concern:

Be it known that I, EMILE GÉRARD, a resident of Limoges, France, in the French Republic, and a citizen of the Republic of France, 5 have invented and produced a new and original Design for a Cuspidor, of which the following is a specification, reference being had to the accompanying drawings, forming part hereof, in which—

10 Figure 1 represents an elevation, partly in section, of my new design for a cuspidor. Fig. 2 represents a top view of the same.

This invention relates to the new form or configuration of a cuspidor, its principal feature being the lower ogee-shaped body and an outer flaring mouth having irregularly-undulated edges, as fully shown in the drawings.

15 In the drawings the letter *a* represents the body, and the letter *b* the mouth of the cuspidor. The body *a*, it will be seen, is ogee-

shaped in such fashion that the convex part of the ogee is above the concave part. The mouth *b* flares outward from its connection with the body *a* and has an outer apparently irregularly-undulated edge *d*. What I mean by "apparently irregular" is that the undulations are of unequal length, as shown in Fig. 2, and, nevertheless, there is a certain regularity arising from the fact that the series of unequal undulations are repeated several times in the circumference of the mouth *b*. 25 30

Having now described my invention, what I claim is—

The design for a cuspidor, substantially as shown and described.

EMILE GÉRARD.
